CLAIM

The ornamental design for a combined bracelet and hair retainer, as shown and described.

DESCRIPTION

FIG. 1 is a front perspective view of a combined bracelet and hair retainer showing my new design;

FIG. 2 is a top plan view thereof, the bottom plan view being a mirror image thereof;

FIG. 3 is a front elevation view thereof;

FIG. 4 is a rear elevation view thereof; and,

FIG. 5 is a right side elevation view thereof, the left side elevation view being a mirror image thereof.

The broken lines shown in FIGS. 1 through 5 illustrate portions of the combined bracelet and hair retainer that form no part of the claimed design.

1 Claim, 2 Drawing Sheets
